CLAIM

The ornamental design for a child-proof eye drop container, as shown and described.

DESCRIPTION

FIG. 1 is an upper right perspective view for a child-proof eye drop container showing my new design;

FIG. 2 is a front view thereof;

FIG. 3 is a back view thereof;

FIG. 4 is a right side view thereof;

FIG. 5 is a left side view thereof;

FIG. 6 is a top plan view thereof; and,

FIG. 7 is a bottom plan view thereof.

The broken line in FIG. 7 depict portions of the child-proof eye drop container that form no part of the claimed design.

1 Claim, 7 Drawing Sheets(56)
